H. B. BURKE,
ANTICREEPING AND ANTISPREADING DEVICE FOR RAILS.
APPLICATION FILED MAR. 3, 1922.

Patented Oct. 24, 1922.

FIG. 1.

UNITED STATES PATENT OFFICE.

HENRY B. BURKE, OF WINDBER, PENNSYLVANIA.

ANTICREEPING AND ANTISPREADING DEVICE FOR RAILS.

Application filed March 3, 1922. Serial No. 540,879.

To all whom it may concern:

Be it known that I, HENRY B. BURKE, a citizen of the United States of America, residing at Windber, in the county of Somerset and State of Pennsylvania, have invented certain new and useful Improvements in Anticreeping and Antispreading Devices for Rails, of which the following is a specification.

10 The present invention relates to devices for preventing the creeping and spreading of rails, especially on the portions of railroad tracks which are curved, and the use of the present invention will undoubtedly prevent many accidents to trains which now take place due to the spreading and creeping of rails. Certain novel specific features and combinations of parts will be fully set out as the description proceeds herein, which go 15 to make the present invention a valuable one for the purpose intended and above mentioned. I am aware that many devices of the kind under consideration have been invented, but it is thought that my invention 20 presents a very complete type of structure for the purpose, possessing as a result of a combination of several features introduced therein, a practical and commercial utility not found in many of the similar devices at 25 present used for a like purpose.

In the accompanying drawings forming part of this specification I have shown one complete example of the physical embodiment of my invention, with some slight 30 modifications, constructed according to the best mode I have so far devised for the practical application of the principles of my invention.

Figure 1 of the drawings is a transverse 35 vertical section of my invention taken on line 1—1 of Figure 3.

Figure 2 is a side elevation of Figure 1.

Figure 3 is a plan view, partly in section of Figure 1.

40 Figure 4 is a side elevation of a portion of a rail showing a bossed projection formed on same, for use with the present invention.

Figure 5 is a plan view of a portion of a rail, portions of which have been removed 45 for purposes of illustration.

Figure 6 is a perspective view of one of the shaped plates used.

Figure 7 is a perspective view of a second

or complementary shaped plate used in conjunction with that of Figure 6.

Figure 8 is a perspective view of a grooved small casting used, and shown in Figure 1 in cross section.

Figure 9 is a perspective view of a slightly modified form of casting similar to Figure 8 of the drawing.

Figure 10 is a section on line 10—10 of Figure 11 of a type of fastening used at rail joints.

Figure 11 is a plan view of Figure 10.

In the drawings the numeral 1 indicates the ordinary T-rail with the exception of certain raised projections 2, 3, 4, 5, formed preferably integral with the web 12 of said rail, the intention being to roll the rails 70 with the raised projections, either in alternate positions such as shown at 4, and 5, of Figure 5, or in opposed positions such as 2, 3 in said Figure, as will be explained below. The size of these projections is clearly illustrated in Figures 1, 2 and 3 of the drawings.

The rail 1 is mounted in the shaped casting 6, the form of which is seen to advantage in Figure 6, having a base portion 7, preferably beveled on its lower face 8, so as to act with 75 the complementary shaped plate 9, as shown in Figure 1. There are also two upstanding legs 10, and 11 shaped as shown to conform with the web 12 and flange 13 of the rail 1, on the shaped plate 6. Between the legs is 80 the recess 14, adapted to accommodate therein the raised projection 3 as shown in Figures 2 and 3 of the drawings. The upper face 15 of the said plate 6 is when in normal position parallel with the upper face 16 of 85 the tie 17, and the end 18 of plate 6 it will be seen from the Figure 1 of the drawing is adapted to enter the recess 19 of the plate 9 as shown.

The shaped plate 9 is best illustrated in 90 the Figure 7 of the drawings, and has a base 20, having a lower face 21, which in normal position as in Figure 1 is parallel with the tie 17 and the upper face 31 of said plate 9 is beveled complementary to the beveled 95 face 8 of the plate 6 as is readily understood. The purpose of the beveled faces on the plates 6 and 9 as can be at once seen, is to enable a firm grip to be taken on the flanges 13, and 22 of the rail 1, by the bent portions 100 of the shaped plates and hold the rail se- 105

curely to the tie 17 by means of the lag-screws 23, 23 as shown. The base plate 9 has a downstanding shoulder 24 on it which engages in the grooved complementary channel 25, to prevent any lateral movement of the rail 1, should the screws 23, 23, become loosened in their sockets from any cause. It is evident that the channel 25 may be secured by the screws 26 to prevent its longitudinal displacement from the tie, and further that the modified type of channel may be used in some cases to advantage. The channels 25 and 27 may both be omitted, and the shoulder 24 on plate 9 is then placed in engagement with a channel formed in the tie itself.

The lag-screws 23, 23, etc., it will be noted have preferably triangular heads, so that the same cannot be tampered with readily when an ordinary wrench is used, thus obviating the likelihood of unauthorized persons loosening said lag-screws. The holes in which the lag-screws are placed are preferably bored holes of proper size, and said holes are preferably creosoted or treated so that the bored threads of the same do not readily decay, and consequently the lag-screws hold into the tie firmly for a long period of time.

The bossed portions 2, 3, etc., it is evident when in normal position engage between the upstanding legs of the shaped plates 6 and 9, and the rail 1 is thus prevented from creeping longitudinally along the ties. As before mentioned the raised projections on the rail may be either alternately positioned as 4, and 5 or opposite each other as 2 and 3. When in alternate position it is evident that the recesses 14 and 28 in the plates 6 and 9 are omitted to suit the condition and the upstanding legs 10, 11, and 29, 30 of the plates 6 and 9 become continuous, and adapted to fit against the web and flanges of the rail 1 when there is no raised projection on the side of the rail nearest to said plates respectively.

This type of anti-creeping and anti-rail spreading fastening is adapted for use on straight tracks and on curved, but attention is called to the fact that when used on curves, the plate 6 is usually placed on the inner side of the curve, as the shaped plate 9, being in immediate contact with the tie, the rail is held more rigidly, and so makes the fastening as a whole more secure. It is also apparent that in some cases it may be found advantageous to use two or three ordinary spiked fastenings on ties which are placed intermediate of those ties which carry the type of fastening illustrated in the present invention, and in this way reduce the number of my fastenings used per rail-length. This reduces the number of raised bosses or projections 2, 3, etc., necessary per rail.

While I have shown the raised projections formed integral with the rail web, and pref-

erably formed on the rail by rolling when the rail is manufactured, it is also evident that the bosses or projections may be added to old rails to accomplish the same purpose, to wit to engage the upstanding legs 10, 11, 70 29, 30 of the plates 6 and 9. In the Figures 10 and 11 of the drawings is shown a device for use with my invention at the joints of rails. 32 indicates a modification of plate 6, while 33 indicates a modification of plate 75 9. The plate 32 is used especially on curves for supporting the outside of the rail, while plate 33 is used as a mate to the same on the inside or inner side of the rail. It is evident that the use of these plates obviates 80 the necessity of bolts at the rail joints when the type of fastening shown in Figures 1 and 2 is used throughout the length of the rails, on the ties which support said rails, other than those near the joint. 85

I claim:—

1. In a device of the class described, a lower shaped plate having an outwardly extending beveled base, and a pair of upwardly extending flanges conforming to the shape 90 of a rail, a transverse shoulder formed on the base of said lower plate, an upper shaped plate having an outwardly extending beveled base formed complementary to the base of the lower plate, and a pair of up- 95 wardly extending flanges conforming to the shape of a rail, a rail mounted between the plates provided with means for engaging the upwardly extending flanges of each shaped plate, to prevent longitudinal displacement of the rail, and means for securing both of said plates to a railroad tie.

2. In a device of the class described, a lower shaped plate having a beveled base, and a pair of upwardly extending flanges 105 adapted to enclose a rail base, a transverse projection on the beveled base of the shaped plate; an upper shaped plate having a beveled base formed complementary to the base of the lower plate, and a pair of up- 110 wardly extending flanges adapted to enclose the base of a rail, a rail having a plurality of raised projections thereon each provided with a portion parallel with the rail web, and a second portion lying parallel with the rail flange, for the purpose of engaging between each pair of upwardly extending flanges for the purpose of preventing longitudinal displacement of the rail. 115

3. In a device of the class described, a lower shaped plate having a beveled base and a pair of upwardly extending flanges adapted to enclose the base of a rail, and forming a U-shaped recess therebetween, a 125 transverse downwardly disposed projection on the base of said lower plate, a tie having a groove formed therein, a channel iron mounted in said groove, in engagement with the projection of the lower shaped plate, an 130

upper shaped plate having a base beveled purpose of preventing longitudinal move- 10
complementary to that of the lower plate, ment of the rail.

a pair of upwardly extending flanges on
the upper shaped plate adapted to enclose

5 a rail base, and forming a U-shaped recess
between said flanges, a rail having a plu-
rality of raised projections formed there-
on each adapted to engage in a U-shaped
recess of one of the shaped plates for the

In testimony whereof I affix my signa-
ture.

HENRY B. BURKE.
